United States Patent Office

Des. 212,191

Patented Sept. 10, 1968

212,191

PET CANTEEN

Joseph C. Mineo, Los Angeles County, Calif.
(6735 Shoup Ave., Canoga Park, Calif. 91304)

Filed Nov. 3, 1967, Ser. No. 9,268

Term of patent 14 years

(Cl. D30—13)

I claim:

The ornamental design for a pet canteen, as shown.
